UNITED STATES PATENT OFFICE.

EDWARD GERSTELL McCANDLISH, OF TAKOMA PARK, MARYLAND.

DESIGN FOR A DOLL.

Application filed July 25, 1924. Serial No. 10,253. Term of patent 7 years.

To all whom it may concern:

Be it known that I, EDWARD GERSTELL McCANDLISH, a citizen of the United States, residing at 20 Westmoreland Avenue, Takoma Park, in the county of Montgomery, State of Maryland, have invented a new, original, and ornamental Design for Dolls, of which the following is a specification, reference being had to the accompanying drawing, forming part thereof.

I claim:

The ornamental design for a doll as shown.

EDWARD GERSTELL McCANDLISH.
